UNITED STATES PATENT OFFICE

ARTHUR E. SCHARF, OF MILWAUKEE, WISCONSIN, ASSIGNOR TO PERELES BROS. INC.,
OF MILWAUKEE, WISCONSIN, A CORPORATION OF WISCONSIN

GOOGLES

Application filed June 30, 1930. Serial No. 464,841.

The invention relates to goggles.

The object of the invention is to provide a pair of goggles that may be economically produced and wherein the metal frames carrying the transparent eyepieces are protected by rims of rubber or other suitable elastic material which may be readily applied to the frames and which are secured thereto without the use of stitching or special fastening means. The invention further consists in the several features hereinafter set forth and more particularly defined by claim at the conclusion hereof.

In the drawings; Fig. 1 is a rear elevation 15 view of a pair of goggles embodying the invention, parts being broken away and parts being shown in section;

Fig. 2 is a plan view of the goggles, parts being shown in section along a center line 20 through the fastening means;

Fig. 3 is a detail sectional view taken on the line 3-3 of Fig. 1.

Referring to the drawings, the goggles include a pair of eyepieces carrying frames 4, eyepieces 5 of glass or other suitable transparent material and rims 16 of rubber or other suitable cushioning material.

Each of the frames 4 are preferably formed from sheet metal to provide a frame portion 6 against which the eyepiece 5 may rest, a bridge support or bridge portion 7 and a side flange portion 8 extending around the frame portion 6 from one side of the hinge support to the other to provide eye-openings 35 but not extending over the hinge support or bridge portion 7 of the goggles; said flange portion tapering as shown in Fig. 2 of the drawings so as to conform to the general shape of the face around the eyes of the 40 wearer.

The outer edge of the flange portion 8 is provided with a short laterally extending edge flange 9 which projects outwardly therefrom and is coextensive with said flange portion except adjacent the bridge portion 7 as at 10, I prefer to bevel said edge flange as shown in Fig. 1. The edges of the flange portion 8 adjacent the bridge are also undercut or formed on an incline extending inwardly from their outer edge as shown at 11,

in Figure 2, for the lower edge of said flange portion.

The eyepieces 5 fit into the frames described above and are held in position therein in any suitable manner as by punching out 55 tongues 12 from the side portions 8 and bending them down against the eyepieces to clamp said eyepieces between said tongues and the frame portions 6.

A hinge 13 has its hinge plate respectively 60 secured to the bridge portion 7 of each frame by rivets 14.

Each rim 16 is as noted above of rubber or other suitable elastic cushioning material and may be initially formed as a ring having 65 a relatively heavy body portion 15 whose outer side is rounded or tapered to improve the appearance of the finished product and having an inwardly extending thinner flange portion 17 adjacent an annular recess 18, said 70 flange extending beyond said recess. This ring or band may be readily applied to the frame previously described by drawing it over the flanged portion thereof so that the edge flange 9 seats in the recess 18 and the inner side of the body portion 15 abuts the flange portion 8 while the flange 17 extends over the edge flange 9 and beyond the same, this ring being put under tension during 75 this operation so that it is tightly held on the 80 eyeframe, it being noted that the undercut or inclined edges 11 under these conditions prevent the cushioning member from slipping off its frame.

It is also to be noted that the rims extend 85 across the open spaces between the side flanges at the bridge piece of the goggles and thus protects that portion of the wearer's face between the eyes.

Any suitable means may be used for holding the goggles in position on the face of wearer as for example the adjustable elastic cord or tape 19 secured to the frames by passing its ends through spaced openings 20 in 90 the side flanges 8.

I desire it to be understood that this invention is not to be limited to any particular form or arrangement of parts except insofar as such limitations are included in the claim. 100

What I claim as my invention is:

In a pair of goggles, the combination of a pair of eyepiece carrying frames, each having an integral bridge portion and side portions terminating adjacent said bridge portion with undercut inclined end edges and with flanged outer edges, said edges inclining inwardly from said flanged edges toward the eye frame, a rim of elastic material for each frame recessed to receive said flanged edges and having a body portion engaging the side portion and end edges of the frame on which it is mounted and held in tensioned engagement therewith.

15 In testimony whereof, I affix my signature.

ARTHUR E. SCHARF.
